UNITED STATES PATENT OFFICE

2,072,922

PENCIL

Clarence F. Norlin, Chicago, Ill.

Application August 19, 1935, Serial No. 36,873

11 Claims. (Cl. 120—18)

The present invention relates to improvements in pencils and more particularly to manually operated feeding mechanisms for pencils of the so-called magazine type, wherein leads to be successively used are fed as needed from the magazine into the tip bore of the pencil, the present invention being an improvement on that set forth in my pending application, Serial No. 735,174, filed November 15, 1934, and in my prior Patent No. 1,937,779, granted me on December 5, 1933.

The primary object of the present invention is to provide a simple feed mechanism adapted to the purpose, which is capable of economic production and highly efficient in use.

Other objects will appear hereinafter.

The invention consists in the combinations and arrangements of parts hereinafter described and claimed.

The invention will be best understood by reference to the accompanying drawing forming a part of this specification and in which:

Figure 1 is an enlarged sectional view taken longitudinally through such a pencil showing a mechanism for the storage of leads and a feeding mechanism adapted to feed leads therefrom and embodying the invention;

Figure 2, is a section taken substantially on the line 2—2 of Fig. 1;

Figure 3 is a section taken on the line 3—3 of Fig. 1;

Figure 4 is a section taken on the line 4—4 of Fig. 1;

Figure 5 is a top plan view of the sleeve and plunger removed from the barrel of the pencil; and

Figure 6 is a sectional view taken on the line 6—6 of Fig. 1.

The embodiment of the invention illustrated in the drawing comprising a barrel 10 having a tip 11 provided with a lead bore 12 and a magazine recess 13 adapted to receive the magazine frame 14, which is provided with a rotatable cylinder magazine 15 having operating spring 15', lead pockets 16 and stops 17, as best shown in Figs. 1 and 6. A more detailed description of the magazine is set forth in my co-pending application, Serial No. 735,174, filed November 15, 1934, and therefore requires no further description here.

The rotation of the magazine 15 serves to register the pockets 16 successively with the tip bore 12, as will be readily understood.

A reciprocating plunger 18 is mounted in a barrel 10 in registration with the lead bore 12 and is arranged to reciprocate in the guide hole 18'.

At its other end the plunger 18 is fixed to a plug 19, which in turn is fixed centrally in a sleeve 20 mounted to reciprocate and rotate freely in barrel 10.

The sleeve 20 is provided with a helical slot 21 which slidably engages a knobbed stud 22 carried by a spring 23 secured to the barrel 10 by the rivet 24, as shown in Fig. 1. The helical slot 10 is provided at its ends with enlarged openings 25 and 26 which permits the radial passage of the knob 27 of the stud 22 into and out of sleeve 20. Plug 19 is provided at its rear end with a cam 28, sleeve 20 with a groove 30, connecting openings 25 and 26 and plunger 18 carries a compression spring 29 as shown. By this arrangement at the foremost point of travel of the plug 19 and the sleeve 20 the knob 27 is pressed outwardly by the cam 28 through the opening 25, where it is free to slide in the groove 30 to the opening 26, this movement being accomplished by the action of the compression spring 29. It is to be further noted, that the stud 22 is held in interlocked engagement with the slot 21 on the forward movement and out of engagement on the return movement of the sleeve 20 by the knob 27.

The sleeve 20 is held against rotation by a lug 31 slidably mounted in a groove 32 on the cap sleeve 33 as shown in Fig. 1. This cap sleeve 33 is provided with an outwardly extending cap 34 which serves as means for rotating the sleeve 20 and is further provided with a peripheral slot 35 into which the pin 36, secured to the barrel 10, is free to travel, thereby permitting its rotation but preventing any longitudinal movement.

In use, upon the rotation of the sleeve 20 by the cap 34 when the parts are in position shown in Fig. 1, the stud 22 travels in the helical slot 21 producing a forward movement of the sleeve 20, the plug 19 and the plunger 18, compressing the spring 29, and forcing a lead 16 forward into the tip bore 12. At the end of the forward movement the knob 27 of the stud 22 is pressed through the opening 25 into the groove 30 thereby releasing the stud from engagement with the slot 21 and permitting the compression spring 29 to move the plunger mechanism rearwardly and to starting position, the spring 23 serving to return the knob 27 through the opening 26 and thereby completing one circle of operations.

While I have illustrated and described the preferred construction for carrying the invention into effect, these are capable of variation and modification without departing from the spirit of the invention. I, therefore, do not wish to be limited to the precise details described, but

desire to avail myself of such variations and modifications as fall within the scope of the appended claims.

I claim:

5. 1. A pencil barrel; a lead magazine mounted in said barrel; a pencil tip having a lead bore and a reciprocating plunger in alignment with and arranged to feed leads from said magazine through said tip bore; rotatable means on said 10 barrel for forwardly actuating said plunger in interlocked engagement; rotatable means for releasing said plunger from said forwardly actuating means; and automatic means for returning said plunger to its retracted position upon the 15 completion of the forward stroke.
2. A pencil barrel; a lead magazine mounted in said barrel; a pencil tip having a lead bore and a reciprocating plunger in alignment with and arranged to feed leads from said magazine through 20 said tip bore; rotatable means on said barrel for forwardly actuating said plunger in interlocked engagement; rotatable means for releasing said plunger from said forwardly actuating means; and spring actuated means for returning said 25 plunger to its retracted position upon the completion of the forward stroke.
3. A pencil barrel; a lead magazine mounted in said barrel; a pencil tip having a lead bore and a reciprocating plunger in alignment with and 30 arranged to feed leads from said magazine through said tip bore; rotatable means on said barrel for forwardly actuating said plunger in interlocked engagement; rotatable means for releasing said plunger from said forwardly actuating 35 means; and means for slidably returning said plunger to its retracted position upon the completion of the forward stroke.
4. A pencil barrel; a lead magazine mounted in said barrel; a pencil tip having a lead bore and 40 a reciprocating plunger in alignment with and arranged to feed leads from said magazine through said tip bore; a tubular feed sleeve connected with said plunger rotatably and slidably mounted in said barrel and having a helical slot in its 45 walls; a stud on said barrel engaging said slot; and means for rotating said sleeve while permitting longitudinal movement thereof.
5. A pencil barrel; a lead magazine mounted in said barrel; a pencil tip having a lead bore and a reciprocating plunger in alignment with and 50 arranged to feed leads from said magazine through said tip bore; a feed sleeve connected with said plunger loosely mounted in said barrel and having a helical slot in its walls; enlarged openings at 55 each end of said slot and a longitudinal groove in its periphery connecting said openings; a spring held knobbed stud on said barrel engaging said slot; and means for rotating said sleeve while permitting longitudinal movement thereof.
6. A pencil barrel; a lead magazine mounted in said barrel; a pencil tip having a lead bore and a reciprocating plunger in alignment with and arranged to feed leads from said magazine through 60 said tip bore; a feed sleeve connected with said plunger loosely mounted in said barrel and having a helical slot in its walls; a stud on said barrel engaging said slot; a rotatable cap on the end of the barrel opposite its tip; a sleeve on said cap 65 telescoping the feed sleeve and having a sliding connection therewith; and a cam on said feed sleeve operating said stud to effect reciprocation of said plunger upon rotation of said cap.
7. A pencil barrel; a lead magazine mounted in said barrel; a pencil tip having a lead bore and a reciprocating spring held plunger in alignment with and arranged to feed leads from said magazine through said tip bore; a feed sleeve connected with said plunger loosely mounted in said barrel and having a helical slot in its walls, enlarged 10 openings at each end of said slot and a longitudinal groove in its periphery connecting said openings; a spring held knobbed stud on said barrel engaging said slot, a rotatable cap on the end of the barrel opposite its tip, a sleeve on said cap telescoping the feed sleeve and having a sliding connection therewith; and a cam on said feed sleeve operating said stud at the forward end, the movement of said feed sleeve to force said stud outwardly through the corresponding opening into said groove.
8. In a pencil, a plunger feed mechanism comprising a pencil barrel; a tubular feeding sleeve rotatably and slidably loosely mounted in said barrel at one end thereof and having a helical slot in its walls; a plunger connected with said sleeve; a stud on said barrel engaging said slot; means guidably positioning said stud relative to said sleeve and slot and means for rotating said sleeve while permitting longitudinal movement thereof.
9. In a pencil, a plunger feed mechanism comprising a pencil barrel; a tubular feeding sleeve rotatably and slidably loosely mounted in said barrel at one end thereof and having a helical slot in its walls; a plunger connected with said sleeve; a spring held stud on said barrel engaging said slot; means guidably positioning said stud relative to said sleeve and slot; and means for rotating said sleeve while permitting longitudinal movement thereof.
10. In a pencil, a plunger feed mechanism comprising a pencil barrel; a tubular feeding sleeve rotatably and slidably loosely mounted in said barrel at one end thereof and having a helical slot in its walls; a plunger connected with said sleeve; a spring held headed stud on said barrel engaging said slot; means guidably positioning said stud relative to said sleeve and slot; and means for rotating said sleeve while permitting longitudinal movement thereof.
11. In a pencil, a plunger feed mechanism, comprising a pencil barrel; a feeding sleeve loosely mounted in said barrel at one end thereof and having a helical slot in its walls, enlarged openings at each end of said slot and a longitudinal groove in its periphery connecting said openings; a spring held knobbed stud on said barrel engaging said slot; a rotatable cap on said end of the barrel; a slideable connection on said cap slideably connecting said sleeve therewith; and a cam on said feed sleeve operating said stud to effect reciprocation of said plunger upon rotation of said cap.

CLARENCE F. NORLIN.
